U.S. Appl. No. 62/486,311, filed Apr. 17, 2017.
(Continued)*Primary Examiner* — Dominic V Simone(74) *Attorney, Agent, or Firm* — Banner & Witcoff, Ltd.(57) **CLAIM**

The ornamental design for a shoe, as shown and described.

DESCRIPTION

FIG. 1 is a rear perspective view of a shoe showing our new design;

FIG. 2 is an opposite side rear perspective view thereof;

FIG. 3 is a side view thereof;

FIG. 4 is an opposite side view thereof;

FIG. 5 is a front perspective view thereof; and,

FIG. 6 is a rear view thereof.

The broken lines depicting the remainder of the shoe show features that form no part of the claimed design.

1 Claim, 6 Drawing Sheets# US D854,303 S
